UNITED STATES PATENT OFFICE.

GEORGES OHLEYER, OF PATERSON, NEW JERSEY.

CREEL.

SPECIFICATION forming part of Letters Patent No. 727,190, dated May 5, 1903.

Application filed September 16, 1902. Serial No. 123,576. (No model.)

To all whom it may concern:

Be it known that I, GEORGES OHLEYER, a citizen of the Republic of France, residing at Paterson, in the county of Passaic and State 5 of New Jersey, have invented certain new and useful Improvements in Creels, of which the following is a specification, reference being had therein to the accompanying drawings.

My invention relates to creels which are 10 used in warping apparatus; and the objects of my invention are to increase the capacity of the creel without materially increasing its size, thus economizing in both labor and floor-space, to increase the efficiency of the frame, 15 and to produce better work.

To increase the capacity of a creel, swinging frames, one inside the other, have been used to support two or more set of bobbins one above the other, each bracket supporting 20 a set of bobbins swinging independently of the others so as to be removed out of the way of the operator when necessary.

My invention consists in a peculiarly-constructed swinging creel-frame adapted to accommodate 25 two or more sets or series of bobbins, a support for said frame and means for locking and releasing any individual bobbin desired without in any way interfering with the location or operation of any of the other 30 bobbins, the construction, arrangement, and operation of which will be hereinafter described.

In the accompanying drawings, in which like numerals of reference indicate similar parts, 35 Figure 1 is a front elevation of my improved creel, showing one position of the bobbin-supporting frame. Fig. 2 is a side elevation of the same. Fig. 3 is a sectional side elevation showing in detail my bobbin-supports and the 40 adjustable locking and releasing device. Fig. 4 is another view of the locking device. Fig. 5 is a sectional detail view on the line *a a* in Fig. 4, and Fig. 6 illustrates the sleeve which is secured in the bobbin-supporting frame 45 and supports the bobbin-spindles.

The main body of the creel 1 is provided with a lower table 1^a and an upper table 1^b, to which the upper and lower supporting arms 25 and 26 of the bobbin-carrying frames 50 11 are pivotally secured. The main body 1 is also provided with the parts 2, to which the

reed 3 is secured, and 2^a, to which the bar-carrying bracket 4 is secured. The brackets 4 are provided with recesses 4^a to receive the ends of the glass bars 5, 6, and 7. The reed 55 3 has compartments 3^a, 3^b, and 3^c to correspond to the vertical compartments 12, 13, and 14 of the bobbin-carrying frames 11. The silk threads pass from the bobbins 15, as follows: the threads S from the bobbins in compartment 14 of the frame 11 to and over the rod 5 and through the compartment 3^c in the reed 3, the threads S' from the bobbin in compartment 13 to and over rod 6 and through compartment 3^b in the reed, and the threads 60 S² from the bobbins in compartment 12 to and over rod 7 and through compartment 3^a in the reed. As shown in the drawings, the bobbin-carrying frame 11 is hung at such an angle that the outer side is higher than the inner 70 side, and thus enables the threads from all the bobbins in each compartment to pass each other to their proper rods and through their proper spaces or compartments in the reed without interfering. (See Fig. 2.) In 75 addition to the fact that the frames 11 are hung at the angle just mentioned it is desired to call particular attention to the further fact that said frames are also hung in a slanting or oblique manner as to their faces, as is shown 80 in Fig. 1. This latter arrangement of hanging permits a great number of bobbins to be mounted in a single frame, so as to be free of access to the operator, who can readily reach any one of the bobbins with his or her hand. 85 Sleeves 18, having a dividing-wall 19^a, separating recesses 19, adapted to receive the ends of the bobbin-spindles 16, are secured in oblique and downwardly-extending slots 17 in the frame 11. Locking-plates 20, having a handle 21 and slots 22, through which securing-screws 23 are passed, and which permit of a longitudinal movement of the plate, and having cut-out portions 24, which may in the movement of the plate register with the 90 oblique slots 17 in the frame 11, serve to lock the spindles in said frame or uncover the slots 17 when the operator desires to remove a bobbin from the frame.

The upper arm 25 has an angle-shaped end 100 25^b, which is pivotally secured to the part 1^b by the screw 25^a, and the lower arm 26 has

not such an angle-shaped end, but is provided with an eye or opening 27, through which screws 27^a pass, securing it to the part 1^a. The oblique or slanting position given to the faces of the bobbin-frames by this construction of the arms 25 and 26 may be accomplished by any other suitable means, and I do not wish to limit myself to the construction shown.

10 The series of bobbin-frames 11 are pivotally connected at their upper ends by the links 28 and at the bottom by the links 29. The links may be secured by screws 29^a or other suitable means.

15 I provide a means to move my series of bobbin-frames in unison when the condition of the work requires it, which consists in devices shown in Figs. 3 and 4, in which 30 is a block with a threaded opening and a pin 31, pivotally secured to the bar 29. Through the threaded opening in the block 30 the screw-threaded bar 32 is operated by means of a lever and handle 33, which may be supported in the fixed bracket 10 or in the part 25 10^a of the frame-support 1 or in any other suitable manner, in order to cause the united bobbin-frames to swing to the right or to the left, as required. In thus swinging the bobbin-frames the dual position thereof (I refer 30 to the slanting surfaces, and the outer edges of the frames being higher than the inner edges) is maintained, so that at no time do the threads of the several bobbins in the same or neighboring compartments interfere with 35 one another, and at all times the operator may readily reach with his or her hand any bobbin needing attention.

It is evident that changes may be made without departing from the principle of my 40 invention.

What I claim as new, and desire to secure by Letters Patent, is—

1. In a creel, a parallelogrammatic frame, having dividing-strips separating the same 45 into a plurality of longitudinally-extending compartments and provided with a series of obliquely and downwardly extending slots, and sleeves, divided into two cylindrical compartments, secured in the bottom of said slots 50 and provided with openings registering with said slots, in combination with spindles loosely fitting in said sleeves, and locking-plates, having cut-out portions registering with said oblique slots, adapted to slide down and over

said slots to lock the spindles therein, substantially as set forth.

2. In a creel, the combination of the main body of the machine with a parallelogrammatic bobbin-supporting frame, longitudinally-extending compartments therein, spindles adapted to hold bobbins loosely mounted in suitable bearings in said bobbin-frame, longitudinally-sliding plates adapted to lock the spindles in said frame and permit them to be removed therefrom, and swinging brackets pivotally securing said bobbin-supporting frame to the main body of the machine, so that the top of the bobbin-supporting frame will incline laterally and backwardly, to permit the examination of, and access to, the bobbins thereon, substantially as set forth.

3. In a creel, the combination with the main body of the machine, of a series of swinging parallelogrammatic bobbin-supporting frames, longitudinally-extending compartments therein, spindles loosely mounted in suitable bearings in said frame, sliding plates to lock or release said spindles, as desired, brackets pivotally securing said bobbin-supporting frames to the main body of the machine so that the tops thereof will incline backwardly and laterally, links pivotally connecting said frames to permit them to swing in unison, and means for swinging said frames in unison, substantially as set forth.

4. In a creel, the main body of the machine, casters attached to the legs thereof, a reed mounted thereon, and a guide-rod-carrying bracket adjustably secured thereto below the reed, in combination with a series of swinging parallelogrammatic bobbin-supporting frames having longitudinally-extending compartments, spindles loosely mounted in suitable bearings in said frames, sliding plates to lock or release said spindles, as desired, 95 brackets pivotally securing said bobbin-supporting frames to the main body of the machine so that the tops thereof will incline backwardly and laterally, links pivotally connecting said frames to permit them to swing 100 in unison, and means for swinging said frames in unison, substantially as set forth.

In testimony whereof I affix my signature in presence of two witnesses.

GEORGES OHLEYER.
